COMBINATION AIR OUTLET AND RETURN WITH FLUORESCENT LIGHTING MEANS

Lee A. Archer, Wheaton, and James S. Kontos, Chicago, Ill., assignors to The Pyle-National Company, Chicago, Ill., a corporation of New Jersey

Filed Jan. 22, 1962, Ser. No. 167,545
9 Claims. (Cl. 98—40)

This invention relates generally to air-lighting troffers wherein the functions of lighting and air distribution or return are combined in one practical unit.

In the lighting field, fluorescent lighting sources were recognized as affording many advantages, particularly the provision of highly increased lighting levels without necessitating the increase of additional electric current or without producing excessive quantities of heat in the space being illuminated. The benefits of using fluorescent lighting sources, however, were offset by the architectural problem of how to deal with fixtures which were large and cumbersome and which presented an interruptive element insofar as the aesthetics of an interior space design were concerned.

In response to such problems, the concept of a recessed troffer was developed wherein the advantages of fluorescent lighting could be obtained while presenting a clean and uncluttered appearance to a ceiling surface.

The problems of ceiling or wall air distribution were, in a sense, comparable to the problems presented in connection with the lighting field, since ceiling diffusers also represented a severe interruptive problem.

By including the air distribution diffuser as a part of the recessed lighting trough, the appearance drawback of ceiling diffusers was eliminated and interior design was enhanced. New problems have been presented in such combined units, particularly where similarly appearing units are used to develop selectively either the function of air distribution or the function of air return.

When used as an air distributor, cooled or heated air is fed from a source at increased pressure to the troffer fixture. When used as a return, the air from the space and at the temperature of the space, is circulated through the fixture and back to the temperature conditioning source.

Since fluorescent lighting fixtures operate most efficiently at a temperature range which is close to normal room temperature, combined units receiving cooled or heated air would tend to establish an operating ambient for the fluorescent lighting means different from the normal room ambient. Accordingly, in conventional troffers of the prior art the difference in operating temperature would produce a color change which would be particularly noticeable if both types of troffers are used in a single ceiling installation.

In accordance with the principles of the present invention, supply air from a temperature conditioned source at increased pressure is discharged through the trough with the assistance of kinetic baffling operable to direct the air through the trough without moving the air in the lighting trough excessively and without appreciable spilling of the conditioned air in the lamp cavity.

Thus, the air-troffer functions effectively as an air distribution troffer providing an ambient for the fluorescent light tubes substantially at an optimum operating temperature. The identical fixture also functions effectively as an air return since return air is permitted to circulate freely through the fixture. Since the return air is at an optimum temperature, the fluorescent tubes will operate close to peak efficiency. By virtue of the utilization of such kinetic baffling in the trough of the air-troffer, the fixture can be designed for perfect color match so the

2

identical fixture can be effectively used as an air distribution-troffer and an air return-troffer.

It is an object of the present invention, therefore, to provide an air-troffer wherein is employed kinetic baffling to direct air flowing through the trough so as to induce an optimum air motion in the trough.

Yet another object of the present invention is to provide an air troffer wherein air flow is channeled without wall enclosed passage means.

10 A still further object of the present invention is to provide an air troffer wherein the air ejector of the troffer is balanced to a neutral point, thereby eliminating any venturi action.

15 A still further object of the present invention is to provide an air troffer suitable for use as either a supply unit or a return unit but wherein air movement within the lighting trough is minimized when used for supply.

Many other objects, features and additional advantages of the present invention will become manifest to those 20 versed in the art upon making reference to the detailed description which follows and the accompanying sheets of drawings in which a preferred structural embodiment of an air troffer is shown and described in connection with the methods contemplated by the present invention.

25 On the drawings:

FIGURE 1 is a somewhat diagrammatic view showing a ceiling construction of a space being illuminated and ventilated incorporating recessed troffers constituting air troffers of the present invention and wherein one or more 30 of the troffers is used as an air distribution troffer, while others are used as air return troffers;

FIGURE 2 is a cross-sectional view taken generally in the plane of line II—II on FIGURE 3;

FIGURE 3 is a cross-sectional view taken generally 35 on the plane of line III—III of FIGURE 2;

FIGURES 4, 5 and 6 are fragmentary cross-sectional views illustrating alternative forms of kinetic baffling in accordance with the principles of the present invention; and

40 FIGURE 7 is a light chart demonstrating the performance of the present invention and wherein relative light output in percent is plotted against supply temperature in degrees Fahrenheit.

As shown on the drawings:

45 In FIGURE 1 there is shown an architectural structure including a ceiling 10 and side walls 11 prescribing the confines of a space 12 to be illuminated and ventilated. The space 12 is provided with a false ceiling 13 spaced from the ceiling 10 to provide a concealed space 50 14 behind the false ceiling 13, which space 14 may also function as a plenum chamber for the reception of return air. Thus, return air is carried from the space 14 via a return conduit 16 to a heat exchanger HE. It will be understood the heat exchanger may constitute either a furnace or an air conditioner, or both, the function of the heat exchanger being to temperature condition a supply of ventilating air which is then pressurized and discharged under pressure through a discharge conduit 17.

55 The heat exchanger is provided with a fresh air inlet 60 shown at 18.

The main air supply duct 19 extends into the space 14 behind the ceiling 13 and is connected to the conduit 17 to receive the supply of pressurized ventilating air.

65 The ceiling 13 has a plurality of openings formed therein as at 20 and in each respective opening there is provided a recessed troffer which may comprise an air distribution troffer as shown at D, or an air return troffer as shown at R. Each distribution troffer D is connected to the main air duct 19 by a length of flexible tubing 21. In accordance with the present invention, the 70 air enters through a valve assembly into a distribution

chamber and then flows in a uniform path through louvered vanes running the entire length of both sides of the troffer. The air flow is controlled by the valve assembly and by kinetic baffling inside the troffer so the air flow is discharged between the shielding frame and the troffer housing.

The return unit R, having no flexible tubing connected thereto, permits return air to be discharged directly into the plenum 14, whereupon the return air flows through the conduit 16 back to the heat exchanger.

Referring now to FIGURES 2 and 3, the structural details of an air-troffer provided in accordance with the principles of the present invention may be observed.

A troffer housing 22 is provided which constitutes a generally inverted U-shaped member divided by a wall 23 into an air distribution chamber 24 and a lighting trough 26.

The housing has an opening 27 formed therein in which is received a collar 28 forming a valve seat 29 and cooperable with an adjustable valve assembly 30, thereby to control the flow of air from the flexible tube 21 which may be conveniently connected to the collar 28, into the air distribution chamber 24.

The wall means 23 constitutes a horizontally extending partition 32 and flanged as at 33 on both sides of the troffer, which flanges 33 are spaced from an adjoining side wall 34 of the troffer housing 22 to form a nozzle 36. It will be noted each nozzle 36 has a wide inlet portion 37 communicating with the air distribution chamber 24 and a restricted throat forming an outlet 38 spaced at a level considerably lower than the horizontal plane of the horizontal partition 32.

Located in the lighting trough 26 and disposed between the vanes 33, 33 are fluorescent light source means taking the form in the embodiment of FIGURE 3 of three elongated fluorescent tubes shown at 40.

A row of louvered vanes 41 run the entire length of both sides of the air distribution chamber 24 and operate to flow supply air from the air distribution 24 in a uniform path into the nozzles 36.

At the bottom of the troffer housing 22, there is located a shielding frame 43 in which is supported suitable shielding, taking the form in the embodiment of FIGURE 3 of a glass plate 44 which extends across the bottom of the lighting trough 26 and which, in effect, forms an extension of the finished surface of the false ceiling 13.

Additional details of the construction described in connection with FIGURE 3 are shown in FIGURE 4. It will be apparent from the foregoing description that the air from the air distribution chamber 24 is discharged in the form of a jet out of the throat of the nozzle 36. Since the air is then free to expand, it may be noted that the theoretically perfect divergence angle of an expansion nozzle handling air would be approximately 9°, the expansion angle being illustrated in dashed lines on FIGURE 4 and identified at 50.

It is contemplated by the present invention, therefore, to locate a scoop 51 having a forward intercepting edge 52 spaced within the angle of divergence of the air stream, thereby to intercept all of the air discharged by the nozzle 36. The scoop 51 is also a turning vane and has a trailing edge 53 which terminates at a curved portion 54, thereby forming with a similarly offset portion 56 on the side wall 34 an outlet passage 57 which extends horizontally outwardly and is then turned downwardly by an offset portion 58 formed on the side wall 34. The shielding frame 43 has an upstanding portion 59 which cooperates with the offset portion 58 to continue the passage 57 and it will be noted the upstanding portion 59 is particularly characterized by a kicker lip 60 disposed at approximately a 45° angle and operative to offset induced secondary air motion. Accordingly, air passing through the passage 57 is pushed downwardly with minimum entrainment and a coalescent air stream is produced.

It will be appreciated that a scoop 51 is provided on both sides of the troffer.

In order to enhance smooth air flow and to cut down possible turbulence, a liner 62 may be affixed to the side wall 34, thereby forming the outside wall of the air passage 57.

By virtue of the arrangement thus provided, use of the troffer as an air distribution troffer is facilitated since supply air will be kinetically baffled by the scoop 51 and directed through the trough 26 without appreciable movement and without producing any venturi action. Accordingly, the fluorescent tubes 40 are permitted to operate in an ideal operating environment close to peak efficiency.

When used as a return, the kinetic baffling provided by the nozzle 36 and the scoop 51 does not interfere with the free circulation of return air through the fixture. However, since the return air passes through the fixture via the passage 57 from the space 12 being illuminated and ventilated, the air is at an optimum temperature and, again, the fluorescent tubes 40 are permitted to operate close to peak efficiency.

In the embodiment of FIGURE 5, there is provided a shielding frame 43a which has an upstanding portion 59a and the scoop previously referred to in the embodiment of FIGURE 4 as at 51 is integrally formed with the shielding frame 43a, shown in FIGURE 5 at 70.

The scoop 70, of course, has a trailing edge which blends into the upstanding portion 59a. The intermediate portion of the scoop 70 is gradually curved and terminates in a forward intercepting lip 71 which, in accordance with the principles of the present invention, is arranged and located within the divergence angle of the nozzle 36, thereby to intercept all of the air discharged out of the throat 38.

The shielding frame 43a is again provided with a kicker lip herein shown at 60a for the purposes previously described.

In the embodiment of FIGURE 6 there is shown a shielding frame 43b having a kicker lip 60b and an upstanding portion 59b. In this embodiment there is provided a dual scoop including a primary scoop 51b having a forward intercepting edge 52b positioned within the divergence angle of the nozzle 36 to catch the primary air in the discharged stream having the greatest kinetic energy. The scoop 51b has a curved portion 54b and a trailing edge 53b disposed in the same manner as the scoop 51 described in connection with FIGURE 4.

The scoop shown at 70b is a secondary scoop of the dual scoop arrangement and has a forward intercepting edge 71b arranged to catch the boundary layer of air which has residual motion and which was not intercepted by the primary scoop 51b. Accordingly, the boundary layer is trapped and is assisted in its motion through the discharge passage by the action of the primary air stream.

Referring now to the light chart of FIGURE 7, the curve shown at A is representative of the performance of a troffer having shielding in the form of a solid lens and without the kinetic baffling of the present invention. The curve shown at B is of a troffer having a completely open lighting trough. The performance of a structure as shown in FIGURES 3 and 4 is illustrated by the curve shown at C, while the performance of the structures of FIGURES 5 and 6 is shown at E and F, respectively. It will be noted on comparing the curves that effective volumes of supply air can be furnished through the troffer of the present invention with minimum air movement in the lighting trough, thereby enhancing the operating efficiency of the fluorescent tubes. Moreover, the same troffer can operate effectively as an air return since the return air circulates freely through the fixture and exposes the fluorescent tubes to an optimum operating temperature.

Although minor modifications might be shown by those versed in the art, it should be understood we wish to embody within the scope of the patent warranted hereon all

such modifications as reasonably and properly come within the scope of our contribution to the art.

We claim as our invention:

1. A recessed troffer for combination with the wall or ceiling of a space to be ventilated and illuminated comprising,

a housing having side walls and forming a trough, a tubular fluorescent light source in said trough to emit rays of light into the space, means for conducting air from a source of increased pressure including an opening in said housing, means including said side walls forming a nozzle connected to said opening and having a restricted throat forming an outlet at the side walls and spaced at a level in said trough lower than said opening, shielding means extending across the bottom of the trough and together with said housing forming an opening adjacent the side wall, and said housing having a separate baffle in said trough below said nozzle,

said baffle having a forward intercepting edge spaced inwardly of the side walls and located within the angle of divergence of the air stream discharged by said nozzle,

said baffle having a turning vane offset transversely outwardly with respect to the side walls to direct the intercepted air outwardly of said trough through said opening and into the space to induce optimum motion of the air in the trough.

2. A troffer housing forming a trough for elongated tubular fluorescent light source means,

said housing having a longitudinal side wall adapted to extend inwardly from a ceiling of a space to be illuminated and ventilated,

nozzle means in said trough near the top thereof and including a vane forming together with said side wall a discharge throat having an upper inlet communicating with a source of ventilating air at increased pressure and a lower outlet for discharging a stream of air downwardly, shielding means extending across the bottom of the trough and together with said housing forming an air outlet, and a scoop member subjacent said throat having a forward intercepting edge located inwardly of said side wall to intercept the air stream discharge from said throat and having a curved turning vane directing the air outwardly with respect to said side wall and into the air outlet with optimum movement of the air in the trough.

3. A combination air outlet-return and lighting fixture for combination with the wall or ceiling of a space to be ventilated comprising,

a housing forming an inverted trough and adapted to be recessed in the wall or ceiling,

and having side walls extending inwardly of the wall or ceiling,

a first baffle member in said trough and including a lip inwardly of and in substantially parallel adjacency to the innermost edge of said side wall and together therewith forming a generally vertically extending air passage having openings at opposite ends thereof for either the return or supply of air, elongated fluorescent light source tubes disposed between said lips,

and a second baffle member in said trough and spaced from one of said air passages adjacent the outermost end of said corresponding side wall,

each said second baffle member having a front intercepting edge disposed inwardly of a corresponding side wall with respect to the air flow angle of divergence of said passage to intercept the air stream discharge out of said passage, said second baffle member having an offset turning vane and a rear edge and said housing com-

prising offset portions at said side wall forming with said turning vane and rear edge an air passage opening into the space being ventilated for discharging the air stream.

4. In a ventilating system, duct means including a flexible tube conducting temperature conditioned air from a source at increased pressure, an air distribution troffer connected to the end of said tube,

and having a distribution chamber formed therein and a valve assembly to control the flow of air into the chamber, louvered vanes running the entire length of both sides of the troffer,

said troffer having a housing forming a lighting trough beneath said distribution chamber and including side walls extending downwardly from said louvered vanes on both sides of the troffer,

a vane in said trough spaced from each said side wall and forming therewith a downwardly extending nozzle means having an outlet at a level below the top of said trough, a shielding means extending across the bottom of said troffer for substantially shielding the trough and forming together with said housing elongated openings transversely outwardly thereof, fluorescent light source means in said trough disposed between said vanes, and a baffle in said trough spaced below said outlet and having a forward intercepting edge disposed inwardly of said side walls to intercept the air discharged from said outlet and having an offset turning vane for directing and discharging the intercepted air through said elongated openings between the shielding means and the troffer housing and out of the troffer.

5. Plural air-troffers recessed in a ceiling to function as air distributing troffers and air return troffers, respectively,

each of said air troffers comprising a housing forming an air distribution chamber having an opening thereinto,

a lighting trough adjacent said air distribution chamber, and passage means between said trough and said chamber,

baffle means on both sides of said trough extending downwardly from said passage means and including a baffle member in spaced relation to the adjoining housing wall to form a nozzle for receiving supply air from said passage means when the troffer is used as a supply troffer and directing the supply air downwardly,

each said nozzle having a diffusion angle of approximately 9° divergence,

fluorescent light source means in said trough between said nozzles, shielding means extending across the bottom of the trough and forming with said housing air passages at the outside portions of said trough, and

a second baffle means having a forward intercepting portion spaced from said nozzle to intercept air from the nozzle and including an offset turning portion directing the air outwardly of the trough into said air passages,

return air circulating freely through said air passages and the trough when the troffer is used as a return air troffer and returning the air to the source via said passage means,

whereby supply troffers and return troffers can achieve an improved color match.

6. An air troffer suitable for use as an air distributor or an air return comprising, a generally U-shaped inverted housing,

said housing having side walls formed with means for connecting said housing in recessed relation in the ceiling of a space to be ventilated and illuminated,

wall means in said housing dividing said housing into an air distribution chamber and a lighting trough and having air passages formed on opposite sides thereof to intercommunicate the chamber and the trough,
 5 vanes on both sides of the troffer extending downwardly from said openings and spaced to form with each respective side wall a nozzle extending from said air distribution chamber toward a lower portion of said lighting trough,
 10 fluorescent light source means in said lighting trough disposed between said vanes, and
 a baffle means on both sides of said trough comprising a vane having a leading edge spaced with respect to each respective side wall in said nozzle to catch air discharged out of said nozzles when said troffer is used to distribute air and having an offset portion offset outwardly with respect to a corresponding side wall, said housing having complementary offset portions forming with said offset portion of 15 said vane air passages opening out of the bottom of the troffer to permit free circulation of room air through said troffer when said troffer is used to return air.
 7. An air troffer as defined in claim 6,
 25 and a shielding frame spaced from and extending between the side walls of said troffer,
 and shielding means closing the bottom of the trough,
 said baffle means being formed integral with said

5

10

15

20

25

- shielding frame and discharging air between the shielding frame and the housing side walls.
 8. An air troffer as defined in claim 6,
 a shielding frame extending between the side walls of said troffer, and
 including in spaced relation to each adjoining side wall a reentrant portion offset at an angle with respect to horizontal to form a kicker lip, said kicker lip offsetting secondary air motion and assisting in pushing supply air downwardly with minimum entrainment to provide a coalescent air stream discharging out of the troffer.
 9. An air troffer as defined in claim 6,
 said baffle means including dual spaced vanes wherein said vane comprises one of said dual vanes and a second vane of complementary shape is spaced therefrom to catch boundary air not intercepted by said first vane.
